COKING LIQUID HYDROCARBONS

Harold V. Atwell, White Plains, N. Y., assignor to
Gasoline Products Company, Inc., Newark,
N. J., a corporation of Delaware

Application March 29, 1933, Serial No. 663,291

1 Claim. (Cl. 202—14)

This application relates to the distillation of liquid or liquefiable hydrocarbons, such as hydrocarbon oils, tars, and pitches, for the purpose of reducing the same to coke.

5 My invention has for an object the provision of a method whereby hydrocarbon material of the character indicated may be reduced to coke in a continuous manner without causing the coke thus formed to adhere to the surface upon which 10 it is supported and having such additional improvements or operative advantages and results as may hereinafter be found to obtain.

15 My invention contemplates introducing a material of the character recited hereinabove, preferably in a heated condition upon a moving bed of preheated finely divided coke or pre-carbonized hydrocarbon material at such a rate that the liquid material is solidified or reduced to a substantially non-fluid condition or coked by the 20 heat of the underlying pre-formed bed of coke before it has had an opportunity to completely penetrate the same, so that the entire bed of carbonized material does not form a homogeneous mass but there remains a layer of material not 25 in a coalesced condition between the newly formed solidified mass of coking or coked material and the support upon which the bed is formed, thereby preventing the newly formed coke from adhering to the support and making 30 possible the easy removal of the coke from the support.

35 My invention further contemplates preheating the coke or carbonized material supplied to the moving support to form a bed thereon, either prior to distributing the coke upon the support or after the bed is formed, the heating being accomplished by any suitable means, as for example, by partial combustion of the coke or by passing hot gas therethrough, or both.

40 While coke from any source may be employed to form the initial bed upon which the material to be coked is sprayed, my invention further contemplates segregating a portion of the coke produced in the process, and preferably the more 45 finely divided portions thereof, and employing the segregated portion of coke to form a preheated bed, and it is an advantage of my invention that when operating in this manner all or a considerable portion of the fines produced may ultimately be combined in the upper portions of the bed with material being reduced to pitch or coke and thus 50 solidified to form masses of relatively large size and relatively high value as compared with more finely divided materials.

55 While in its simplest form my invention con-

templates the formation of a preheated bed of coke or the like upon a moving support, the subsequent introduction thereon of material to be coked, and finally the removal of the coke, my invention further contemplates, where desired, subjecting the combined bed of materials to further heating or combustion and further introduction of material to be coked, the combined bed in this instance passing through a plurality of alternated heating and carbonizing zones.

10 My invention further contemplates the segregation of the materials forming the bed after the coking or carbonizing operation has been completed in such manner as to afford a separation of the remaining portions of the underlying bed 15 of finely divided material and the relatively more valuable mass or layer of coke overlying the same.

15 It will be understood that the term "coke" as employed herein may designate products within a rather wide range of properties, due to the 20 fact that various materials coke at different temperatures, and due also to the fact that carbonization is a more or less gradual change. As the terms are generally used in the art, "coke" is a 25 carbonized non-liquefiable material having a definite cell structure, while "pitch" is a material having a determinable melting point and not having a definite cell structure, but there are materials lying within an intermediate range which are extremely difficult to classify as coke 30 or pitch.

35 The term "coke" as employed herein therefore does not exclude a product so hard as to be practically indistinguishable from a true coke, nor semi-coke, nor a "low-temperature coke", nor a product consisting in part of true coke and part of pitch, as any of such products, as well as a true coke, may be produced by means of my invention, and the specific nature of the final product will vary with the nature of the material or materials treated and the temperature at 40 which the coking or carbonizing proceeds.

45 While my invention is especially suitable for the coking or carbonizing of petroleum hydrocarbons such, for example, as residuums obtained in distilling or cracking petroleum or petroleum oils, it may also be employed for the coking of other hydrocarbon liquids or liquefiable hydrocarbon materials, such, for example, as coal tar, water-gas tar, oil-gas tar and other tars, and 50 pitches obtained therefrom. Mixtures of material of petroleum and non-petroleum origin may also be coked in accordance with my invention. Thus I may employ my invention for the purpose of making a high-grade or metallurgical coke 55

from petroleum coke of relatively low-grade character, as for example by spraying tar or the like into a bed of the latter and coking the whole at a high temperature, preferably in excess of about 5 1300° F.

I may also employ my invention to coke various materials of liquefiable character such for example as "amalgams" of coal and non-solvent oil or solutions of coal in tar, tar oil or other hydro-10 carbon oil having solvent properties with respect thereto. Such materials may vary in character from materials purely liquid at atmospheric temperature to materials which are semi-solid or solid at atmospheric temperature.

15 In most instances, it is preferred to introduce the material to be coked at an elevated temperature, for example, from about 200° to about 850° F. Thus, residuum drawn off hot from an oil-cracking or distilling operation may be discharged 20 directly, without substantial cooling, upon the bed where it is to be coked.

It is not necessary, however, that the material to be coked be heated prior to its introduction onto the coking bed. Thus, in the case of pitch 25 or other material solid at atmospheric temperature, while it is preferred to discharge these upon the coke bed at such temperature that they are fluid and may be introduced through a suitable spraying means, such materials may be introduced 30 in a solid or semi-solid condition where desired, the introduction of material in this condition being facilitated by pulverizing the same prior to their introduction.

The coke or carbonized or partly carbonized 35 material from which the underlying bed is formed is preferably in a finely divided condition, and may be similar in origin to the material being coked or may be derived from other sources. Thus, cokes obtained from coal, coal-tar pitch, 40 petroleum oils and the like may be employed, petroleum coke being preferred, and the material to be coked may in each case comprise an oil, tar or pitch either from a similar origin or from a different origin; thus the bed being subjected to coking may comprise petroleum coke and 45 coal tar or coal-tar pitch.

The temperature at which the coking operation is conducted may vary considerably from a low-temperature coking range of, for example, from 50 about 800° F. to 1300° F., to a high-temperature coking range of, for example, from about 1500° to 2000° F., in accordance with the character of the material treated and the nature of the results desired and it will therefore be understood that, in 55 its broad aspect, my invention is not limited to any specific temperature within a range suitable for coking or substantial coking.

In order that my invention may clearly be set forth and understood, I now describe, with reference 60 to the drawing accompanying and forming part of this specification, a preferred form and manner in which my invention may be embodied and practiced. In this drawing,

Figure 1 is more or less diagrammatic vertical 65 sectional view of apparatus for carbonizing liquefiable hydrocarbon material in accordance with my present invention; and

Figure 2 is a similar view on enlarged scale of a portion of the apparatus illustrated in Figure 1.

70 Similar reference numerals designate similar parts in both of the views of the drawing.

Referring now to the drawing, carbonization is effected upon a moving support comprising an endless chain or belt 1 mounted upon and driven 75 by sprocket wheels 2. Such travelling supports

are known in the art of coking and are similar to chain-grate stokers except that in the present instance the interstices between the various links or plates forming the chain 1 are preferably made small enough to prevent such materials as coke 5 breeze from falling through the same in any substantial amount. As is indicated by the arrows shown in connection with the sprocket wheels 2, the upper surface of the chain support 1 moves from left to right as shown in Figure 1.

10 For the purpose of maintaining a supply of previously coked material, such, for example, as petroleum coke, pitch coke, or coke made from coal, to be supplied to the moving support 1, I provide a chamber 3 which is connected by means 15 of a passageway 4 having a feed-regulating device 5 to the interior of a chamber 6 which encloses the support 1.

20 Coke may be supplied to the chamber 3 through a charging device comprising a closed feed hopper 7 having a charging valve 8 and a filling valve 9. The valves 8 and 9 are adapted to be operated alternately, whereby coke may be charged into the chamber 3 from time to time as desired without permitting the escape of gases from the interior of the chamber 3 through the charging opening. Such charging devices are common in the art of gas manufacture and need not be described in further detail here.

25 Coke, preferably in a heated condition, is delivered from the chamber 3 to the support 1 through the passageway 4 at such rate that it forms a uniform bed 11 having a thickness of, for example, from 2" to 8", upon the moving support 1. Where the material comprising the bed 30 11 is not already in a sufficiently highly heated condition, air or other heating gas may be supplied through a duct 12 communicating with a gas supply conduit 13. The air or other heating gas, for example, hot gases of combustion, or the 35 hot products of complete or partial combustion produced by thus blasting the coke bed 11, passes from the interior of the chamber 6 through a duct 14 having a branch duct 15 leading to the lower portion of the chamber 3. By means of valve 40 devices 16 and 17 located in the ducts 14 and 15, respectively, all or a portion of the hot gases passing through the duct 14 may be diverted to 45 pass through the body of coke within the chamber 3, from which they are removed through a 50 duct 18.

Air or other heating gas may also be supplied directly to the interior of the chamber 3 from a conduit 21 having a valve 22 and communicating with the interior of the chamber 3 through a 55 grate or perforated wall 23. Such coke or ash as may drop through the openings in the grate or wall 23 are permitted to drop into a hopper 24 having a removable cover 25 or other suitable device for removing material deposited in the 60 hopper 24.

Thus, I may bring the coke bed 11 to incandescence by introducing air through the conduit 13 and duct 12, and the products of combustion 65 may be passed wholly or entirely through the coke in the chamber 3 to preheat the same, additional air being supplied, if desired, through the conduit 21 and the grate 23 to assist in the pre-heating of the coke, either by direct combustion of the same or by combustion of carbon monoxide 70 in the gases of combustion entering the chamber 3 through the duct 15.

The gases leaving the upper surface of the bed 11 are prevented from escaping to other portions of the interior of the chamber 6 by means of 75

spaced vertical walls 30 and 31 having drag links 32 and 33, respectively, adapted to ride on the upper surface of the support 1 or the bed 11, as the case may be, and adapted to form a sufficient seal against passage of gases therethrough.

The coke bed 11 thus passes under the wall 31 and drag links 33 in a highly heated condition, preferably at such temperature as to be incandescent, and in any event not below 1300° F., and immediately after passing under the wall 31, hydrocarbon material to be coked is introduced on to the upper surface of the highly heated coke bed 11. Thus, in Figure 1, I have illustrated a spray 35, of which a plurality may be employed, 15 which is supplied with hydrocarbon material in a liquid state through a conduit 36 having a valve 37 and communicating with a suitable source (not shown) of such material. By way of example, residual petroleum oil may be supplied to the spray or sprays 35 in a highly heated condition from a suitable point in a cracking or distilling 20 operation.

Where hydrocarbon material to be coked is solid at the temperature at which it is introduced, 25 although liquefiable at the temperature of the bed 11 prior to coking thereof, some suitable means for feeding material in solid form on to the bed 11 may be substituted for the sprays 35. For example, a passageway and flow regulating 30 means similar to those illustrated at 4 and 5, respectively, may be substituted for the sprays 35, conduits 36 and valves 37.

The rate of introduction of the hydrocarbon material is so regulated in accordance with the 35 depth and temperature of the bed 11, the temperature of the material being introduced and the coking tendency of the hydrocarbon material to be coked, as well as other factors which will be apparent to those skilled in the art, as to cause 40 the hydrocarbon material introduced to the top of the highly heated bed 11 to be coked or at least reduced to a substantially non-fluid condition before it penetrates the full depth of the bed 11, so that substantially no material in a 45 fluid or sticky condition reaches the upper surfaces of the moving support 1.

It will, of course, be apparent that in actual practice, especially when working with a relatively thin bed 11, it will be practically unavoidable 50 to completely prevent material introduced through the spray 35 from coming into contact with the moving support 1 at any point, but the introduction of the hydrocarbon material may easily be regulated so that full penetration of 55 the bed 11, if it occurs at all, occurs only to a very minor extent and in isolated spots, so that substantially none of the troublesome adherence of sticky material or coke in the process of formation which has been experienced in the prior 60 art takes place in accordance with my invention, and the newly formed coke may readily be removed from the support 1 due to the fact that the mass of newly formed coke (both after and before coking is completed) is separated at substantially 65 every point from the surface of the moving support 1 by a layer of coke in a non-sticky and non-coalescent condition.

A third wall or partition 40, having drag ends 41 adapted to ride on the upper surface of the bed 42 of newly formed coke which overlies the initially supplied bed 11, is provided at a sufficient distance from a wall 31 to allow for substantially complete coking of the hydrocarbon material introduced through the sprays 35. The 75 gases and vapors liberated during the coking

operation are removed from that portion of the interior of the chamber 6 lying above the support 1 between the walls 31 and 40 through an off-take pipe 45 leading to a collecting main 46 which may serve a plurality of coking chambers 5 6 arranged side by side. The off-take pipe 45 is preferably provided with a regulating valve 47 and with valved sprays 48 communicating with a source 49 of gas oil, tar, or the like. Such oil may be introduced to the off-take 45 and the main 46 to prevent formation and deposition of coke from heavy pitch within the latter. The main 46 is preferably connected to an exhaust 10 (not shown) which is so regulated as to maintain either a substantially atmospheric pressure 15 or a pressure a little below or a little above atmospheric in the carbonizing space within the chamber 6.

Situated below the upper surface of that portion of the support 1 lying between the walls 31 20 and 40, I may provide a plurality of refractory-walled flues 51, through which heating gases may be passed for the purpose of transferring additional heat to the material lying upon the moving support 1 to promote the coking operation. 25

While the material passing under the wall 40 may be removed from the apparatus as a whole, without attempting to separate it into its constituents, I prefer to separate the newly formed 30 bed of coke 42 from the remaining portions of the bed 11. I may accomplish this by suitable means such, for example, as an adjustable plate 53 located near the righthand end of the support 1 as shown in the drawing. The sharp forward edge of the plate 53 is so adjusted with 35 respect to the support 1 as to divide the material moving forward on the support 1 at a point which marks the substantial termination of the bed 42 of newly formed coke or, if desired, at a slightly lower point where the plate 53 passes 40 readily through the advancing residual portion of the coke bed 11.

It will, of course, be obvious that the upper 45 portions of the coke bed 11 will be largely combined with and absorbed into the newly formed coke bed 42, and it is one of the advantages of my invention that a considerable part of the relatively finely divided coke comprising the underlying bed 11 may thus be combined or "recoked" 50 in such manner as to produce coke of larger size and consequently increased value.

That portion of the coke which passes under the plate 53 is removed by suitable means, for example, a conveyor 55, while that portion of the coke which passes over the upper surface of the plate 53 may be delivered to a second conveyor 56 which removes it from the chamber 6. A suitable water spray 57 may be provided for the purpose of quenching all or a portion of the coke, and the steam vapors liberated by such quenching may be removed through an off-take 60 conduit 58.

For the purpose of removing any small portions of coke or sticky, partly-carbonized material which may occasionally adhere to the surface of the travelling support 1, I provide a rotating member 60 preferably having a toothed or serrated surface as shown. It will be understood, however, that it is one of the advantages 70 of my present invention that such adherence of coke or sticky material to the support 1 is reduced to a minimum and that with properly controlled operation the member 60 may be found unnecessary, and in any event its purpose is 75

merely to provide against incidental irregularities in the operation of the process.

As an alternative mode of operation, the material charged into the highly heated coke bed 11

5. may comprise a pasty or semi-solid mass obtained by mixing coke with a liquefiable hydrocarbon material. The low fluidity of such a mixture, especially when prepared by mixing heated coke with tar, pitch or the like, serves to provide
10. a further safeguard against passage of liquid through the interstices of the support 1, and reduces the depth of the bed 11 required.

While I have illustrated and described a preferred form of apparatus by means of which my invention may be practiced and embodied, it will readily be understood by those skilled in the art that my process is adapted to be performed in apparatus of various kinds, such, for example, as that described and claimed in the copending application of William F. Moore, Serial No. 654,846, filed February 2, 1933, in which petroleum oils are distilled and coked by radiant heat from a suitable source on a bed of non-liquefiable carbonaceous material fed on to a moving support.

25. It will further be understood that my process is not limited to the details of the various illus-

trative examples which have been set forth hereinabove, but is to be broadly construed within the scope of the claim hereinafter made.

I claim:

The method of coking heavy hydrocarbon oil 5 which comprises forming a bed of loose, non-cohesive petroleum coke pieces upon a moving support, heating said bed to a temperature substantially in excess of a minimum coking temperature for said oil, then supplying said oil to 10 the upper portion of said heated bed as it is moved forward upon said support, and regulating the temperature, the rate of introduction of the oil, the rate of travel of the bed on the support and the thickness of the bed of coke to effect a sufficient devolatilization and carbonization of the oil under the influence of the highly heated coke bed as the oil penetrates the upper portion of the coke bed to prevent said oil from reaching the bottom of the coke bed in a liquid condition, and 20 maintaining the coke bed and the oil supplied thereto at a coking temperature for a sufficient time to complete the coking of said oil and thereby forming a dense oil coke.

25

HAROLD V. ATWELL.
